Primary Examiner — Michelle E. Wilson*Assistant Examiner* — Caitlin A Laverty(74) *Attorney, Agent, or Firm* — ScienBiziP, P.C.(57) **CLAIM**

The ornamental design for a rifle bag as shown and described.

DESCRIPTION

FIG. 1 is a front, right and top perspective view of a rifle bag, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1; and, FIG. 11 is an enlarged view of detail 11 in FIG. 1.

The dashed broken lines depict portions of the rifle bag that form no part of the claimed design. The dot-dash broken lines in FIGS. 1 and 9-11 depict the boundaries of the enlargements and form no part of the claimed design.
